CLAIM

The ornamental design for a lounge chair, as shown and described.

DESCRIPTION

FIG. 1 is a front and right side perspective view of a lounge chair showing my new design;

FIG. 2 is a front elevation view thereof;

FIG. 3 is a right side elevation view thereof, the left side being a mirror image;

FIG. 4 is a top plan view thereof;

FIG. 5 is a rear elevation view thereof; and,

FIG. 6 is a close-up view of a weave pattern on the lounge chair.

The broken lines show environmental subject matter and form no part of the claimed design. The fragmentary showing of a weave pattern in FIGS. 1, 3, 4, and 5, and as shown in detail in FIG. 6, is understood to be repeated throughout the surfaces shown.
